GEORGE A. BURNHAM, OF SAUGUS, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

CIRCUIT INTERRUPTER

Application filed February 1, 1930. Serial No. 425,295.

This invention relates to electric switches and circuit interrupters, especially to the oil-immersed type.

One of the objects of the present invention 5 is the provision of a switch or interrupter which is so arranged that the circuit interrupting arc is directed against a cold body having good heat conducting ability so that the arc is caused to be rapidly cooled and 10 extinguished; and further arranged so that when the arc has been extinguished and the switch is open, the space between said arc cooling body and the conducting parts of the switch are occupied by thick masses of 15 oil whereby to provide adequate insulation between the terminals of the switch.

Another object of the invention is to support the aforesaid arc cooling body on the movable switch member.

20 In an oil-immersed circuit interrupter, the circuit interrupting arc is directed magnetically, either by the natural shape of the current path through the switch or by a specially provided current path, toward the side 25 wall of the enclosing casing. If the current to be interrupted is severe, the arc may be deflected far enough to come in contact with the side wall or the insulating lining thereof. Thus, a further object of the invention is 30 to locate the arc cooling body between the wall of the enclosing casing and the arcing members, so that the arc is prevented from impinging directly against the wall.

35 A further object is to provide a plurality of closely-spaced heat-absorbing metal plates, which preferably are carried by and are movable with the movable switch member, in such relation with the arc which is drawn between the arcing members under the oil that the arc is caused to play against the plates and pass into the spaces therebetween whereby to be cooled and extinguished.

40 A further object is generally to improve circuit interrupters and circuit interrupting methods.

Fig. 1 is a side elevation of a circuit interrupter embodying the present invention, the enclosing oil containing casing being 45 shown in section and details of the inter-

rupter, unnecessary for the understanding of the present invention, being omitted.

Fig. 2 is a view similar to Fig. 1 but with the circuit interrupter in open condition.

Fig. 3 is a section taken along line 3-3 55 of Fig. 2.

Fig. 4 is a perspective view of one of the arc cooling plates of Figs. 1 and 2.

Fig. 5 is a plan view of a modified construction of the movable switch member 60 adapted for association with the stationary switch members of Figs. 1 and 2.

Fig. 6 is a detailed side elevation of the bank of arc cooling plates at one end of the 65 movable switch member.

Fig. 7 is a sectional detail of a modified arrangement of arc cooling plates.

Fig. 8 is a plan view of Fig. 7.

The present invention is applied to the circuit interrupter described and claimed in the copending application of Chester D. Ainsworth, Serial No. 242,666, filed December 27, 1927, now Patent No. 1,762,604, dated June 10, 1930, and assigned to the assignee of the 70 present application.

75 The interrupter includes the insulated stationary switch members 10 having conducting studs 12 to the lower ends of which the inverted laminated or brush members 14 are secured. Auxiliary contact or arcing members 16 in the form of cylinders are located beneath the main contact members 14 and are supported in frames 18 fixed to the studs 12. The movable switch member includes the lifting rod 20 which carries a bridging member 22 at its lower end and which connects and bridges the two brush members and thereby carries the current through the switch when the switch is closed. The stationary arcing members 16 are engaged by similar movable arcing members 24. Said movable arcing members are secured to the outer ends of conducting arms 26 the inner ends of which are pivotally secured to or are fulcrumed on the upturned inner ends 28 of conducting and supporting members having sections 30 which are disposed below said arms 26 and other sections 32 which are disposed above said arms thereby forming, in effect, current conducting loops which set up magnetic fields 80 85 90 95 100

that react on the magnetic fields surrounding the current carrying arms 26 in a direction which urges said arms, and the arcing members carried thereby, upwardly or into forcible engagement with the stationary arcing members 16. The magnetic flux set up by said loops also traverses the arc zones between said separable arcing members in a direction which is angularly related to the 10 current paths through the arcs and is also such as to deflect said arcs outwardly or respectively toward the right and left. Said current carrying member is supported on the lower end of the lifting rod 20 below the 15 bridging member 22 and within a frame 34 which has depending side walls or legs 36 which overlie the conducting member. The aforesaid parts are contained within an oil containing enclosing casing having the metal 20 side wall 38 and the insulating lining 40 which is disposed between the side wall and the separable arcing members. Normally, the oil in which the switch members are immersed occupies the space between the side 25 wall and the separable switch members although, when the switch opens under heavy current, the oil may be displaced and the space occupied by the gases resulting from the circuit interrupting arc.

30 In accordance with the present invention, means are provided against which the circuit interrupting arc is brought in contact whereby to cool the arcs and effect their rapid extinguishment. Also in accordance 35 with the present invention, the said arc-cooling means are located between the separate arcing members and the side wall of the enclosing casing whereby to prevent the arc from coming directly into contact with the 40 side wall and also to cool the gases down to such a temperature that they cannot damage the side wall and have no material conductivity when and if they ultimately do contact with the side wall in rising to the top of the 45 casing.

In the construction illustrated in Figs. 1 through 4, the arc cooling means consists of relatively thick and massive plates 42 which are composed of a metal as copper that has 50 good heat absorbing ability and which are located sufficiently close to the separable arcing members so that the arcs are brought magnetically into heat-dissipating engagement therewith. Said plates are vertically disposed beside said arcing members and extend on opposite sides therebeyond for a sufficient distance to occupy the entire transverse width of the zone. Said plates, at the bottom, are provided with inturned lugs 43 which are secured by screws 44 to insulating bars 46 which extend beneath the arcing members and are secured by bolts 48 to the legs 36 of the frame 34. The plates 42 are spaced a sufficient distance from the conducting paths of the stationary switch members so that the oil there-

between provides adequate insulation therebetween both when the switch is closed and when the switch is opened and the circuit interrupting arcs have been extinguished. The plates are high enough so that when the switch opens there is a sufficient vertical extent of the plates presented to the action of the arcs so that the arcs are cooled and quenched by the time the switch is completely opened. The arrangement also is such that when the switch opens the oil in which the parts are immersed will not be deflected away from the plates and the movable arcing members but can flow freely therebetween and thus provide maximum insulation therebetween. With this arrangement, the magnetic field provided by the loops forces the arcs outwardly and into engagement with the arc cooling plates 42 so that the arcs are caused to become rapidly cold and extinguished. Said plates are interposed between the arcing members and the side walls of the casing and so prevent the arcs from coming into contact with the side wall and function to cool the arc gases sufficiently to render them harmless if they should come into contact with the side walls as the gases pass upwardly through the oil.

In the construction illustrated in Figs. 5 and 6, a modified arrangement is provided. A plurality of arc-cooling and heat-conducting plates 50 are located adjacent the arcing members and are vertically arranged in parallel spaced relation and present their inner narrow edges to the arcs. Said plates are preferably insulated from each other and, to this end, are supported in spaced relation on insulating tubes 52 and are secured together between the end plates 54 by bolts 56 which pass through said tubes and said end plates. Said end plates are secured to the ends of the aforesaid insulating bars 46. The spaces between the plates are relatively narrow, say, approximately the thickness of a plate, and are freely open at all sides so that oil and arc gases can pass freely therebetween. As thus arranged, the circuit interrupting arcs are blown by the magnetic fields of the loops against the plates and into the spaces between the plates 50 and into intimate heat-transferring engagement with the broad faces of the plates thereby to cool the arcs rapidly. The arc gases that emerge from between the plates at the outer edges thereof remote from the arcing members are cool and so cannot cause trouble when and if they engage the insulating lining 40 or the metal side wall 38 of the enclosing casing. For some purposes, it may be advantageous to have said plates 50 connected electrically together in which event the plates can be mounted directly upon the bolts 56.

In the modification shown in Figs. 7 and 8, the arc cooling plates 58 are generally horizontally extended in vertically spaced relation and are also inclined upwardly and out-

wardly from the arc zone between the stationary and movable arcing members 16 and 24. The plates are located between and are supported by preferably insulating plates 60 the

5 lower ends of which are attached to the insulating bars 46. With this arrangement, as before, the circuit interrupting arc is blown against the front edges of the plates and into the spaces between the plates and thus is caused to cool and become extinguished. The plates, being upwardly inclined, direct the cool arc gases upwardly so that they are not so liable to come in contact with the side wall of the enclosing casing.

10 15 In the modifications shown in both Figs. 5 and 7, the plates are arranged to be materially beneath and away from the live parts of the stationary switch members, as with the modification shown in Fig. 1, so as to provide 20 good insulation between the terminals of the switch when the switch is open.

25 In all of the modifications, the arc cooling plates are normally insulated from the switch circuit and from ground at least to such a degree that no material amount of current can flow from the plates either to ground or to the switch circuit external of the arc when the circuit interrupting arc is in contact with the plates. The arc cooling plates, being carried 30 by the movable switch member, are moved downwardly through the cool oil upon switch opening movement and thus are kept cool at the time they are active in cooling the arc gases.

35 35 The oil in which the switch members are immersed can be replaced with any other suitable insulating medium if desired.

The structure can be otherwise modified without departing from the spirit of the invention.

I claim:

1. A circuit interrupter having the combination of an oil containing enclosing casing, separable arcing members immersed in the oil in said casing, and an insulated metal plate immersed in the oil between the wall of said casing and said arcing members and located in a plane parallel with the line of separation of said contact members and in position to intercept the circuit interrupting arc drawn between said contact members and prevent it from engaging said wall, said plate also having good heat-absorbing ability and adapted to cool the circuit interrupting arc.

55 2. A circuit interrupter having the combination of an oil containing enclosing casing, separable arcing members immersed in the oil in said casing, and an insulated metal plate immersed in the oil between the wall of said casing and said arcing members and located in a plane parallel with the line of separation and at one side of said contact members and in position to intercept the circuit interrupting arc drawn therebetween and prevent it from engaging said wall, said plate also hav-

ing good heat-absorbing ability and adapted to cool the circuit interrupting arc, and means to direct the circuit interrupting arc to lie against said plate along the length thereof.

3. A circuit interrupter having the combination of an oil containing enclosing casing, separable arcing members immersed in the oil in said casing, and a continuous heat-absorbing arc-cooling body located between said arcing members in a plane parallel with the line of separation of the contact members and between said contact members and the wall of said casing and adapted to intercept the circuit interrupting arc drawn therebetween and cool it.

4. A circuit interrupter having the combination of an oil containing enclosing casing, separable arcing members immersed in the oil in said casing, a heat-absorbing arc-cooling body located alongside and between said arcing members and the wall of said casing and disposed in a plane parallel with the line of separation of the contact members and adapted to intercept the circuit interrupting arc and cool it, and means to direct the circuit interrupting arc to lie against said arc-cooling body along the length thereof.

5. An electric oil switch having a stationary switch member including stationary arcing members, a movable switch member including a movable arcing member, and a heat-absorbing arc-cooling body carried by and movable with said movable switch member and disposed alongside and in position to be engaged by the circuit interrupting arc drawn between said arcing members when the switch opens under load, said body being moved through the oil by said movable switch member when the switch opens.

6. An electric switch having a stationary switch member including an arcing member, a movable switch member including an arcing member, means providing a body of oil in which the arc is drawn, and a heat-absorbing arc-cooling body insulated from said arcing members and carried by and movable with said movable switch member and disposed adjacent and in a plane parallel with the line of separation of said arcing members in position to be engaged by and to cool the circuit interrupting arc along its length.

7. An electric switch having a stationary switch member including an arcing member, a movable switch member including an arcing member, a heat-absorbing arc-cooling body insulated from said arcing members and carried by and movable with said movable switch member and disposed alongside and in a plane parallel with the line of separation of said arcing members in position to be engaged by and to cool the circuit interrupting arc drawn therebetween, and means to maintain an insulating liquid between said body and said arcing members when the switch is open.

8. An electric switch having stationary and movable arcing members, a heat-absorbing arc-cooling body carried by and movable with the movable arcing member and disposed generally parallel with the line of separation of said arcing members in position to be engaged by and to cool the circuit interrupting arc between said arcing members along its length, and means to direct the circuit interrupting arc to lie against said body along its length.

9. An electric switch having stationary and movable arcing members, a heat-absorbing arc-cooling body carried by and movable with the movable arcing member and disposed in a plane parallel with and in position to be engaged by and to cool the circuit interrupting arc between said arcing members and which constitutes a barrier to the lateral expansion of said arc, and magnetic means to direct the circuit interrupting arc against and into intimate contact with said body throughout its length.

10. An electric switch having stationary and movable arcing members, a stack of heat-absorbing arc-cooling plates carried by and movable with the movable arcing member and disposed in position to present their edges to the circuit interrupting arc between said arcing members, and magnetic means arranged to direct the circuit interrupting arc against said stack.

11. A circuit interrupter including an oil containing enclosing casing, separable arcing members immersed in the oil therein, and a plurality of closely-spaced heat-absorbing and arc-cooling plates which are insulated from the interrupter circuit and are disposed adjacent the separable arcing members in planes parallel with the line of separation of said arcing members and in position to be engaged by the circuit interrupting arc and to cool the arc, each of said plates presenting a continuous heat-absorbing surface alongside the arc which is adapted to abstract heat from the arc throughout its length.

12. A circuit interrupter having separable arcing members, an arc cooling plate disposed in position to be acted on and to cool the arc gases of an arc drawn between said arcing members, and means to move said plate through a liquid body so as to move the liquid over the gas-engaging surface of said plate at the time it is engaged by the arc gases.

13. A circuit interrupter including separable arcing members, an arc cooling device including spaced arc cooling plates between which the arc gases can be located, and means independent of any action of the arc gases to circulate a cooling fluid body in the spaces between said plates at the time the arc exists.

14. A circuit interrupter including separable arcing members, an arc cooling device including spaced arc cooling plates between

which the arc gases can be located, and means independent of any action of the arc gases to circulate a cooling fluid body in the spaces between said plates at the time the arc exists, comprising means to move said plates in the direction of their lengths through a cool fluid body during the separation of said arcing members.

In testimony whereof, I have signed my name to this specification.

GEORGE A. BURNHAM.
